US0D1010888S

(12) **United States Design Patent** (10) Patent No.: **US D1,010,888 S**
(45) Date of Patent: ** Jan. 9, 2024

(54) **VEHICLE FRONT BLADE AND HEADLIGHTS ASSEMBLY**

(71) Applicant: **FERRARI S.p.A.**, Modena (IT)

(72) Inventor: **Flavio Manzoni**, Modena (IT)

(73) Assignee: **FERRARI S.p.A.**, Modena (IT)

(**) Term: **15 Years**

(21) Appl. No.: **29/900,429**

(22) Filed: **Aug. 21, 2023**

Related U.S. Application Data

(62) Division of application No. 35/515,626, filed on Aug. 19, 2022 (U.S. filing date under 35 U.S.C. 384), and having an international filing date of Aug. 19, 2022.

(57) **CLAIM**

The ornamental design for a vehicle front blade and headlights assembly, as shown and described.

DESCRIPTION

FIG. 1 is a front perspective view of the vehicle front blade and headlights assembly showing my design;

FIG. 2 is a rear perspective view thereof;

FIG. 3 is a front elevation view thereof;

FIG. 4 is a right-side view thereof;

FIG. 5 is a rear elevation view thereof;

FIG. 6 is a top plan view thereof;

FIG. 7 is a bottom view thereof;

FIG. 8 is an enlarged front view thereof; and,

FIG. 9 is an enlarged front perspective view thereof.

The broken lines are for the purpose of illustrating environmental structure that forms no part of the claimed design.

1 Claim, 9 Drawing Sheets
